UNITED STATES PATENT OFFICE.

FREDERICK A. RUFF, OF DETROIT, MICHIGAN, ASSIGNOR TO THE DETROIT AUTOMATIC SWITCH COMPANY, LIMITED, OF SAME PLACE.

SWITCH-OPERATING MECHANISM.

SPECIFICATION forming part of Letters Patent No. 591,144, dated October 5, 1897.

Application filed February 3, 1897. Serial No. 621,752. (No model.)

To all whom it may concern:

Be it known that I, FREDERICK A. RUFF, a citizen of the United States, residing at Detroit, in the county of Wayne and State of Michigan, have invented certain new and useful Improvements in Switch-Operating Mechanism, of which the following is a specification, reference being had therein to the accompanying drawings.

10 My invention relates to that class of railway-switches in which the switch may be operated from a car moving upon the track.

The invention consists in the peculiar construction, arrangement, and combination of 15 parts, and particularly in the construction of the intermediate mechanism between the movable rail of the switch and its actuating arm or tread, whereby successive actuations of said arm or tread will throw the switch alternately in opposite directions, all as more 20 fully hereinafter described and claimed.

In the drawings, Figure 1 is a sectional perspective view of my switch-throwing mechanism. Fig. 2 is a cross-section thereof.

25 A are the stationary rails of the track, and B is the movable or switch rail.

C is a tread or movable arm secured in bearings in the road-bed a short distance in front of the switch and in a position to be depressed 30 by an arm depending from the car when the latter passes over the track. This tread is connected to the arm of a lever D, fulcrumed at E and extending to a point opposite the switch-rail B.

35 F is a rocking lever or walking-beam pivotally secured to a standard G above the end of the lever D and extending transversely of the track.

H is a rock-arm connected to the walking-beam F, and I is a link connecting the end 40 of this rock-arm to the switch-rail B.

J is a connecting-rod between the end of the lever D and the walking-beam F. At its lower end this rod is pivotally secured to the 45 lever D and has a sliding connection at its upper end with the walking-beam, preferably by slotting the beam longitudinally and providing the upper end of the rod with an anti-friction-roll a, adapted to run in said slot.

50 All the mechanism so far described is enclosed in a suitable casing, such as K, buried in the road-bed.

The parts being constructed as shown and

described, their operation is as follows: When the car passes along the track, the motorman 55 or driver, wishing to throw the switch, depresses a lever or arm on the car so that it will strike and depress the tread C as the car passes over it. This will cause the movement of the lever D, which will raise the connecting-rod J and rock the walking-beam, the latter moving the arm H and the link I, while as soon as the operation is completed and the tread C is released the weight of the long arm of the lever D will cause it to fall again, carrying the rod J down with it, the roll a running down the slot to the opposite end of the walking-beam. The parts will now be in a position to move the rail in the opposite direction, when the tread is again depressed. 60 Thus it will be seen that with each successive depression of the tread the switch is thrown in the opposite direction. This greatly simplifies the mechanism, as it does away with the necessity of having two treads 65 in the road-bed and two operating-arms on each car, which is usual in other constructions.

What I claim as my invention is—

1. The combination with the movable 80 switch-rail and its actuating arm or tread, of intermediate mechanism between said arm or tread and rail, comprising a walking-beam and a reciprocating and oscillating connecting-rod slidingly secured to the beam adapted in its forward stroke to rock said beam and to slide to the opposite end thereof in its return stroke.

2. The combination with the movable switch-rail and its actuating arm or tread, of 85 intermediate mechanism between said arm or tread and rail, comprising a lever connected at one end to said tread and extending beneath said switch-rail, a walking-beam connected to said rail and a reciprocating and oscillating connecting-rod between said lever and beam slidingly secured to the latter, and adapted in its forward stroke to rock the beam and to slide to the opposite end thereof in its return stroke. 90

In testimony whereof I affix my signature in presence of two witnesses.

FREDERICK A. RUFF.
